[57] **CLAIM**

The ornamental design for an underwater camera, as shown and described.

DESCRIPTION

FIG. 1 is a perspective view of an underwater camera showing my novel design;

FIG. 2 is a left side elevational view thereof;

FIG. 3 is a front side view thereof;

FIG. 4 is a top plan view thereof; and,

FIG. 5 is a back side view thereof.

The broken lines shown in all views are for environmental purposes only and form no part of the claimed design.
